Inventors:

UNITED STATES PATENT OFFICE.

WILLIAM H. JAMOUNEAU, OF NEWARK, AND JUSTUS VERSCHUUR, OF JERSEY CITY, NEW JERSEY, ASSIGNORS TO B. F. NORRIS, ALISTER & CO., OF CHICAGO, ILLINOIS.

DESIGN FOR A SPOON.

SPECIFICATION forming part of Design No. 22,500, dated June 6, 1893.

Application filed March 21, 1893. Serial No. 467,082. Term of patent 3½ years.

To all whom it may concern:

Be it known that we, WILLIAM H. JAMOUNEAU, residing at Newark, in the county of Essex, and JUSTUS VERSCHUUR, residing at Jersey City, in the county of Hudson, State of New Jersey, citizens of the United States, have invented and produced a new and original Design for Spoon or Flat-Ware Handles; and we do hereby declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a front view of a spoon of our design, and Fig. 2 is a reverse view of the same.

20 The leading feature of our design consists in a spoon handle having the configuration and ornamentation on the front, and back, substantially as shown and described and finally embraced in the clauses of the claim.

25 In said drawings, *a* indicates the handle, at the wider end of which on the front face, is displayed an oblong or oval medallion, *b*, having a representation, *c*, of Columbus thereon, and, around it, a series of scrolls *d*, *d*, *d*, 30 which give outline to the handle. Below the medallion, the series of scrolls is continued and the handle is narrower in width to a point, *e*, where it is again enlarged and dis-

plays the figure of a sailing vessel, *v*, of antique design, the enlargement being bordered with scroll-shaped ornamentation *g'*. Below this, in turn, the handle is more narrow and at the opposite edges has long concave curves, *f*, commonly found at the shanks of spoon handles. At the reverse side of the handle, 40 the outlines and the ornamental scrolls are closely similar in shape and disposition to those of the opposite side. Toward the wide end of the handle, is displayed a perspective view of the Administration building *g*, of the 45 World's Columbian Exposition; below this is a plain shield, *h*; below this, in turn, a representation of a globe, *i*, and at the head of the shank, *j*, a disk-shaped representation or ornamentation *k*.

50

What we claim as new is—

1. The design for a handle, for spoons substantially as shown and described.

2. In a design for a handle, for spoons, the obverse, substantially as shown and described.

55

3. In a design for a handle, for spoons, the reverse, substantially as shown and described.

In testimony that we claim the foregoing we have hereunto set our hands this 10th day of March, 1893.

WILLIAM H. JAMOUNEAU.
JUSTUS VERSCHUUR.
